UNITED STATES PATENT OFFICE.

ANTOINE VÉRICEL, OF BALDWIN, NEW YORK, ASSIGNOR TO DOEHLER DIE-CASTING CO., A CORPORATION OF NEW YORK.

DESIGN FOR A SUPPORT FOR RADIOCABINETS OR THE LIKE.

Application filed November 30, 1928. Serial No. 29,069. Term of patent 3½ years.

To all whom it may concern:

Be it known that I, ANTOINE VÉRICEL, a citizen of the Republic of France, and a resident of Baldwin, in the county of Nassau and State of New York, have invented and produced a certain new, original, and ornamental Design for Supports for Radiocabinets or the like, of which the following is a specification, reference being had to the accompanying drawings, forming part thereof, wherein—

Fig. 1 is a perspective view showing the supports of my design as they appear when in use, and

Fig. 2 is an enlarged detail view of the upper and lower extremities of one of the supports.

I claim:

The ornamental design for a support for radiocabinets or the like, as shown.

ANTOINE VÉRICEL.
